UNITED STATES PATENT OFFICE.

SAMUEL Y. MERCHANT, OF BOSTON, MASSACHUSETTS.

DESIGN FOR A LADY'S GARMENT.

59,562.

Specification for Design.

Patented Nov. 1, 1921.

Application filed December 11, 1920. Serial No. 430,068. Term of patent 14 years.

To all whom it may concern:

Be it known that I, SAMUEL Y. MERCHANT, a citizen of the United States, residing at Boston, in the county of Suffolk and State of Massachusetts, have invented a new, original, and ornamental Design for a Lady's Garment, of which the following is a specification, reference being had therein to the accompanying drawings.

The accompanying drawing is a side elevation of my new design for a lady's garment.

In the embodiment of the invention the part 4 shows through the part 1, and the drawing illustrates the design as it would appear to purchasers and users.

I claim:—

The ornamental design for a lady's garment, as shown.

In testimony whereof, I hereunto affix my signature.

SAMUEL Y. MERCHANT.
